DESIGN FOR A CHILD'S FOLDABLE CHAIR

Genevive E. Frush, Los Angeles, Calif.

Application June 18, 1947, Serial No. 139,792

Term of patent 3½ years

(Cl. D15—8)

To all whom it may concern:

Be it known that I, Genevive E. Frush, a citizen of the United States, residing in the city and county of Los Angeles and State of California, have invented a new, original, and ornamental Design for a Child's Foldable Chair, of which the following is a specification, reference being had to the accompanying drawing, forming part thereof.

Fig. 1 is a front elevation of a child's foldable chair showing my new design.

Fig. 2 is a vertical section on line 2—2 of Fig. 1.

Fig. 3 is a top plan view of the chair shown in Fig. 1.

I claim:

The ornamental design for a child's foldable chair, substantially as shown.

GENEVIVE E. FRUSH.
